RETRACTABLE FURNACE SLURRY SPRAYER
Robert E. Chappell, Lancaster, Ohio, assignor to Diamond
Power Specialty Corporation, Lancaster, Ohio, a cor-
poration of Ohio

Filed May 21, 1963, Ser. No. 281,971
3 Claims. (Cl. 239—186)

The present invention broadly pertains to spraying apparatus and more particularly to an improved extractable type sprayer adapted for mounting on a wall of a heat exchanger apparatus for automatically spraying a liquid or slurry of a chemical additive into the interior of the boiler.

Various techniques and apparatuses have heretofore been used or proposed for use in connection with the injection of chemical additives in the form of solutions or suspensions into the interior of various types of heat exchanger apparatuses. Some of these techniques include the addition of the additive in the fuel for discharge through the burner nozzles, the manual spraying of the additive at selected locations, as well as incorporating additive conduits in conventional soot blowers employed for discharging a high pressure blowing medium against the heat exchanger surfaces for effecting a dislodgement of the soot, slag, and other extraneous deposits thereon. The latter technique has been found eminently satisfactory in most heat exchanger installations. In some instances, however, it has been found desirable to inject such chemical additives at locations which are not serviced by soot blowers equipped with additive injecting means or alternatively, to supplement the additive injected by the soot blower. The apparatus comprising the present invention is particularly applicable for adapting a heat exchanger apparatus with a chemical additive system without necessitating a modification of the cleaning equipment originally installed.

The furnace sprayer comprising the present invention is particularly applicable for injecting chemical additives such as magnesium oxide and/or calcium oxide in the form of an aqueous slurry against the heat exchanger surfaces of direct-fired combustion apparatus to effect a reduction in the corrosion of such heat exchanger surfaces and to increase the ease by which the deposits such as soot and slag can be removed therefrom by conventional boiler cleaning equipment. Effective control of corrosion and slag deposition requires periodic treatment of the heat exchanger surfaces with a prescribed quantity of the slurry additive. The automatic operation of the furnace sprayer comprising the present invention enables it to be readily adapted to an automatic sequentially phased control system incorporating a plurality of such sprayers which can be operated in a preselected sequentially phase sequence at preselected time intervals. Automatic systems of this type substantially eliminate the problems associated with a haphazard treatment of heat exchanger surfaces as encountered by manually operated sprayers which require considerable attention and manpower to provide the requisite treating function.

It is accordingly a principal object of the present invention to provide an automatic remotely actuatable furnace sprayer which overcomes the problems and disadvantages associated with manual type sprayers of the types heretofore known.

Another object of the present invention is to provide an improved furnace sprayer which on actuation is operative to automatically effect a discharge of a liquid chemical additive in the form of a fine sized spray into the interior of a heat exchanger apparatus and thereafter is automatically retracted and the interior of the spray tube is purged by a high pressure air blast to remove any residual liquid chemical thereon.

Still another object of the present invention is to provide an improved furnace sprayer which is of simple design, of durable operation, of versatile installation, and of economical manufacture and operation.

5 The foregoing and other objects and advantages of the present invention are achieved by a furnace sprayer adapted for mounting on the wall of a heat exchanger apparatus and including a spray tube formed with a nozzle in the forward end thereof which is reciprocable to and from an inoperative retracted position to an operative projected position and which spray tube incorporates actuator means thereon for automatically actuating valve means responsive to the reciprocating movement thereof for starting and stopping the flow of liquid treating additive into the spray tube and for starting and stopping a pressurized purging gas maintaining the interior of the spray tube in a substantially clean condition preparatory to the next operating cycle. It will be appreciated that while the furnace sprayer comprising the present invention is particularly applicable for injecting a treating slurry against the heat exchanger surfaces of direct-fired heat exchanger apparatus, the sprayer can also be satisfactorily employed in other installations wherein periodic automatic spray application of fluids is required.

10 The manner of accomplishing the foregoing objects, and other objects and features of the invention, will become apparent from the following detailed description of an embodiment of the invention when read with reference to the accompanying drawings in which:

15 FIGURE 1 is a side elevation view partly in section of a slurry furnace sprayer constructed in accordance with the preferred embodiment of the present invention removably mounted on the exterior surface of a boiler;

20 FIG. 2 is a magnified plan view of the furnace sprayer shown in FIGURE 1;

25 FIG. 3 is a side elevation view of the furnace sprayer shown in FIGURE 2;

30 FIG. 4 is a transverse vertical sectional view through the furnace sprayer shown in FIGURE 3 and taken along the line 4—4 thereof;

35 FIG. 5 is a perspective view of the underside of the furnace sprayer shown in FIGURES 1—3.

40 FIG. 6 is an enlarged plan view partly in section and partly in phantom illustrating in particular the arrangement of the piping for supplying pressurized air to the furnace sprayer; and

45 FIG. 7 is a magnified fragmentary sectional view of an orifice port in the piping arrangement shown in FIGURE 6 and taken along the line 7—7 thereof.

50 Referring now in detail to the drawings, the slurry furnace sprayer comprising the present invention comprises a frame including a longitudinally extending member 10 of an inverted U-shaped configuration which is securely affixed at its forward end to a mounting plate 12. A pair of gussets 14 are preferably rigidly welded to the mounting plate 12 and member 10 for reinforcing the framework. The mounting plate 12 is formed with a plurality of apertures 16 therethrough for removably securing the furnace sprayer such as by means of bolts to a plate 18 mounted in a port 20 of a wall 22 of the heat exchanger apparatus. The plate 18 and the mounting plate 12 of the sprayer framework is formed with a pair of aligned holes 24 through which the nozzle end portion of a spray tube 26 projects and is movable therethrough during the projecting and retracting movement of the spray tube.

55 60 65 70 75 The forward end portion of the spray tube 26, as best seen in FIGURES 2 and 3, is formed with a nozzle head 28 having at least one small hole (not shown) therein through which the fluid chemical additive is discharged during operation of the sprayer unit. The particular type of nozzle head 28 and the disposition of the discharge

holes therein can be selected so as to provide the desired spray configuration in accordance with the disposition of the heat exchanger surfaces to be treated.

In the exemplary installation shown in FIGURE 1, the spray tube and nozzle head are disposed in the fully retracted position wherein the nozzle head is located within the port 20 and out of direct contact with the hot combustion gases within the interior of the boiler. Any heat absorbed by the forward face of the nozzle head 28 is quickly conducted outwardly along the spray tube which is located exteriorly of the boiler and at a relatively low ambient temperature. During operation of the furnace sprayer, the spray tube and nozzle head are reciprocated to a fully projected position as shown in phantom in FIGURE 1 wherein the nozzle head is disposed beyond the water wall tubes 30 disposed along the inner surface of the boiler wall 22. While in the fully projected position a liquid treating additive such as an aqueous slurry of calcium oxide and/or magnesium oxide for example, is discharged from the nozzle head in a manner such that the fine sized droplets impinge on the heat exchanger surfaces to be treated.

The reciprocation of the spray tube 26 to and from the inoperative position and the projected position is achieved by a double acting air-actuated cylinder 32 which is affixed to the inner surface of a web 34 of the member 10 such as by means of bolts 36 and is positioned with its piston rod 38 disposed in substantial longitudinal alignment with the hole 24 in the mounting plate 12. The end of the piston rod 38 is secured to a T fitting 40 into the other end of which the rearward end of the spray tube 26 is threadably disposed in pressure-sealing relationship. A slide block 42 is adjustably affixed to the rearward end of the spray tube 26 adjacent to the T fitting 40 such as by means of a set screw 43 as may be best seen in FIGURE 4.

An actuator pin 44 is threadably engaged in the slide block 42 and projects upwardly through a longitudinal groove or slot 46 extending along the forward portion of the web 34 of the member 10. The actuator pin 44 is movable along the slot 46 in response to the reciprocating travel of the spray tube and during which travel the actuator pin coats with and pivotally rotates a bifurcated cam 48 of an air valve 50 and a bifurcated cam 52 of a liquid slurry valve 54. To avoid the accumulation of dust and other extraneous deposits on the cams 48, 52, a cover shield 55 is preferably mounted on the frame as best shown in FIGS. 3 and 4.

The cams 48, 52 as best seen in FIGURES 2-4 are oriented relative to the slot 46 and actuator pin 44 so as to be moved from the positions as shown in solid lines in FIGURE 2 to the positions as shown in phantom which are disposed approximately 90° from the original position shown. Each of the cams 48, 52 are provided with an inwardly extending slot 56 which flares outwardly at the outer ends thereof indicated at 58 to facilitate engagement and disengagement with the actuator pin 44. The cam 48 when in the position as shown in solid lines in FIGURE 2 places the air valve 50 in the open position. Movement of the cam 48 from the position as shown in solid lines to the position as shown in phantom effects a closing of the air valve 50. On the other hand, when the cam 52 is in the position as shown in solid lines in FIGURE 2, the slurry valve 54 is disposed in the closed position. Rotation of the cam 52 to the position as shown in phantom in FIGURE 2, effects an opening of the slurry valve 54.

The supply of an aqueous slurry or other suitable liquid additive chemical to the interior of the spray tube is achieved by a main supply header 60 disposed exteriorly of the wall of the boiler to which a supply pipe 62 is connected for supplying slurry to each individual furnace sprayer unit. A main shutoff valve 64 is incorporated in each supply pipe 62 for manually shutting off the supply of slurry to the spray unit as may be re-

quired from time to time to permit service of the unit. The supply pipe 62 is connected to the inlet side of the slurry valve 54 and the outlet of the slurry valve is connected to a T fitting 66 by means of a pipe 67 which is clamped to the member 10 by means of a U-bolt 69. The outlet of the T fitting 66 is connected by means of a flexible conduit or hose 68 to the T fitting 40 at the rear end of the spray tube. The flexible hose 68 enables unrestricted reciprocating movement of the spray tube relative to the framework of the spray unit.

10 The other side of the T fitting 66 is connected to the outlet side of the air valve 50 by means of a pipe or tube 70. The inlet side of the air valve 50 is connected to a check valve 72 which in turn is connected to the outlet side of a chamber or air pressure accumulator 74 which is clamped to the side of the frame member 10 by means of a U-bolt 75. The check valve 72 is oriented so as to prevent flow of treating slurry into the accumulator 74 and attendant tubing network in the event of malfunction of the air valve 50 or slurry valve 54.

15 The air pressure accumulator 74 is provided with a T fitting 76, as best shown in FIGURES 5 and 6, mounted on the wall thereof intermediate to its ends. Each of the sides of the T fitting 76 is connected to a check valve 78, 80 which are oriented to permit the flow of air into but not out of the accumulator. The inlet side of the check valve 78 is connected by means of a tube 82 to a T fitting 84 mounted on and disposed in communication with the rod end of the pneumatic cylinder 32. The tube 82 is connected by means of a tube fitting 86 to the T fitting 84 and is provided at that connection with an orifice disc 88 to restrict the flow of air to the accumulator. The other branch of the T fitting 84 is connected by means of a tube 90 to an outlet port 92 of a solenoid actuated control valve 94.

20 The other check valve 80 connected to the T fitting 76 mounted on the pressure accumulator is connected at its inlet side by means of a tube 96 to a T fitting 98 mounted on and disposed in communication with the blank end of the pneumatic cylinder 32. The tube 96 is connected to the T fitting 98 in a manner similar to the connection between the tube 82 and fitting 84 employing an orifice disc 100 as best seen in FIG. 7 to restrict the flow of air therethrough. The other outlet branch of the T fitting 98 is connected by means of a tube 102 to a T fitting 104 connected to a second outlet port 106 of the control valve 94. The other branch of the T fitting 104 is provided with an orifice disc 108 for a purpose subsequently to be described.

25 The control valve 94 is of the solenoid actuated type well known in the art and is formed with the first outlet port 92 and second outlet port 106 which are connected to the pneumatic cylinder and pressure accumulator in a manner as previously described and as best seen in FIGURE 6. The control valve 94 is also formed with an inlet port 110 which is adapted to be connected by means of a tube 112 to a source of high pressure air which is operable to effect pneumatic actuation of the air cylinder 32, for purging the interior of the spray tube at the completion of a spraying cycle, and for supplying a continuous low volume stream of air for discharge through the nozzle head during the period of inoperation of the spray unit maintaining the nozzle holes open and for cooling the spray tube and the nozzle head thereon. The control valve 94 incorporates a resiliently biased valve mechanism therein which when the solenoid is in the deenergized condition, places the outlet port 92 in communication with the inlet port 110 maintaining a positive pressure at the rod end of the cylinder 32 and thereby maintaining the spray tube in the fully retracted position. At the same time a continuous bleed of air flow passes through the orifice disc 88 through the air pressure accumulator for discharge into the spray tube and then out through the holes in the nozzle head thereon. Upon energization of the control valve 94, the valve mechanism is moved so as to place the inlet port 110 in communication with the

outlet port 106 applying high pressure air to the blank end of the cylinder effecting movement of the piston rod and spray tube to the fully projected position while simultaneously effecting a buildup of pressure within the pressure accumulator.

It will be apparent from the foregoing that automatic control of the furnace spray unit is achieved simply by energizing the solenoid of the control valve 94 for a pre-selected time period at the expiration of which the de-energization of the solenoid causes the spray tube to automatically retract and to be purged of residual slurry thereby placing it in a standby condition for the next operating cycle. In view of the simplicity provided in accordance with the spray unit comprising the present invention, a plurality of such units can readily be incorporated in a control system providing for a sequentially phased operation of each unit in a preselected sequence. Suitable electrical timing means can be incorporated in such a system for energizing each control valve and maintaining that valve energized for a preselected time period to enable the injection of a prescribed quantity of liquid additive into the interior of the heat exchanger apparatus. Alternatively, each unit can be energized remotely such as by a control button on the master operating panel which may incorporate a suitable adjustable time delay relay for maintaining that spray unit energized for a selected time interval.

The operation of the spray unit will now be described with particular reference to FIGURES 2, 5, and 6. With the furnace spray unit in a standby condition, the spray tube 26 is in the fully retracted position and the cams 52 and 48 are in the positions as shown in solid lines in FIGURE 2 such that the slurry valve 54 is closed and the air valve 50 is open. In this standby condition, high pressure actuating air supplied from the supply line 112 to the control valve 94 is transmitted from the outlet port 92 to the rod end of the air cylinder 32 by means of the T fitting 84, maintaining a positive pressure against the piston holding the spray tube in the retracted position. The air in the T fitting 84 bleeds through the orifice disc 88 passing through the tube 82 and check valve 78 into the pressure accumulator 74 from which it is discharged through the check valve 72 and open air valve 48 through the tube 70 and T fitting 66 into the flexible hose 68 connected to the T fitting 40 at the rearward end of the spray tube 26. This constant trickle of air is discharged through the nozzle head 28 serving the dual function of maintaining the nozzle ports clear and cooling the nozzle head and forward end portion of the spray tube during inoperation.

The commencement of the operating cycle of the spray unit is simply achieved by energizing the solenoid of the control valve 94 which moves its valve component so as to close communication between the inlet port 110 and outlet port 92 and open communication between the inlet port 110 and outlet port 106. Accordingly, high pressure actuating air is diverted from the rod end of the air cylinder 32 to the blank end thereof through the tube 102 and T fitting 98 whereupon the piston rod 38 and the spray tube connected thereto commence their projecting travel. During the projecting travel of the piston rod 38, the air in the rod end of the cylinder is discharged out through the T fitting 84 and aperture disc 88 and passes into the accumulator 74 by means of the tube 82, check valve 78 and T fitting 76. The orifice disc 88 provides sufficient restriction so as to provide a cushioning effect and preventing the piston from moving too rapidly toward the fully projected position. The air thus entering the accumulator 74 is discharged into the spray tube until such time that the air valve 50 is closed in response to the advancing movement of the spray tube. With the control valve 94 in this position, the quantity of air which is discharged through the orifice disc 108 in the T fitting 104 is negligible in comparison to that which is transmitted through the tube 102 into the blank end of the cylinder 32 effecting forward movement of the piston therein.

As the spray tube moves toward the projected position,

the actuator pin 44, as best seen in FIGURE 2, contacts the slot 56 of the cam 48 moving it from the position as shown in solid lines to the position as shown in phantom effecting thereby a closing of the air valve 50. Upon a closing of the air valve 50, the air pressure transmitted through the orifice disc 88 through the tube 82 and through the orifice disc 100 through the tube 96 into the pressure accumulator 74 effects a progressive buildup of air pressure therein.

During further continued projecting travel of the spray tube, the actuator pin 44 coacts with the cam 52 effecting a movement thereof from the position as shown in solid lines in FIGURE 2 to the position as shown in phantom whereupon the slurry valve 54 is opened. Accordingly, the liquid treating additive such as an aqueous slurry supplied from the supply header 60 through the open shutoff valve 64 passes through the slurry valve 54 and T fitting 66 through the flexible hose 68 and is discharged into the T fitting 40 at the rearward end of the spray tube 26. The pressurized liquid additive is discharged from the nozzle head 28 with the spray tube in substantially the fully projected position as shown in phantom in FIGURE 1. The spray tube is maintained in the fully projected position by the positive pressure applied to the blank end of the pneumatic cylinder 32. While in the fully projected position, air pressure continues to accumulate in the pressure accumulator 74 via the bleed of air passing through the orifice disc 100, tube 96 and check valve 80 and eventually approaches the pressure of the air supplied through the supply tube 112.

At the expiration of the spray period, as determined by a suitable timer, for example, the solenoid of the control valve 94 is deenergized effecting a movement of the valve component therein so as to place the inlet port 110 in communication with the outlet port 92 and to close communication between the inlet port 110 and outlet port 106. Accordingly, pressurized air is directed into the rod end of the pneumatic cylinder 32 through the tube 90 and T fitting 84 effecting an initiation of the retracting movement of the spray tube. During the retracting movement of the piston in the pneumatic cylinder 32 the blank end of the cylinder is vented through the T fitting 98 and tube 102 and the air is discharged through the orifice disc 108 providing sufficient restriction so as to retard and cushion the retracting movement thereof.

As the spray tube retracts the actuator pin 44 coacts with the cam 52 moving it from the position as shown in phantom in FIGURE 2 to the position as shown in solid lines effecting thereby a closing of the slurry valve 54. Accordingly, the flow of slurry to the spray tube is halted. During the further retracting movement of the spray tube, the actuator pin 44 coacts with the cam 48 moving it from the position as shown in phantom in FIGURE 2 to the position as shown in solid lines effecting an opening of the air valve 50. As the air valve 50 is opened, the accumulated air pressure in the pressure accumulator 74 is discharged through the check valve 72, tube 70, T fitting 66, flexible hose 68 and T fitting 40 into the rearward end of the spray tube 26. This high volume surge of pressurized air serves to purge the residuary slurry or liquid additive in the supply conduits and spray tube preventing any residual accumulation therein which might otherwise have a tendency to foul the nozzle ports.

When the spray tube attains its fully retracted position and at the completion of the discharge of the air from the pressure accumulator 74, a continuous trickle of air is discharged from the spray tube as provided by the orifice disc 88 in a manner as previously described. The furnace sprayer unit is again in the standby condition preparatory to its next operating cycle.

While it will be apparent that the embodiments of the invention herein disclosed are well calculated to fulfill the objects of the invention, it will be appreciated that the invention is susceptible to modification, variation and change

without departing from the proper scope or fair meaning of the subjoined claims.

What is claimed is:

1. A spray apparatus comprising a frame, a spray tube movably mounted on said frame and formed with a nozzle in the forward end portion thereof, an air operated means connected to said spray tube for effecting reciprocation thereof to and from a retracted position and a projected position, first conduit means including a first valve for supplying a pressurized liquid additive to said spray tube, second conduit means including a second valve for supplying pressurized air to said spray tube, supply means including control means for supplying pressurized air to said air operated means and said second conduit means, coacting means on said spray tube and said first and said second valve for engaging and closing said second valve and thereafter engaging and opening said first valve in response to the projecting travel of said spray tube and for closing said first valve and opening said second valve in response to the retracting travel of said spray tube, pressure accumulating means disposed in communication with said supply means and said second conduit means for accumulating air under pressure upon closing of said second valve and for discharging the accumulated air and purging said spray tube upon the opening of said second valve.

2. A spray apparatus comprising a frame, a spray tube movably mounted on said frame and formed with a nozzle in the forward end portion thereof, an air cylinder connected to said spray tube for effecting reciprocation thereof to and from a retracted position and a projected position, first conduit means including a first valve for supplying a pressurized liquid additive to said spray tube, second conduit means including a second valve for supplying pressurized air to said spray tube, supply means including control means for supplying pressurized air to said cylinder and said second conduit means, coacting means on said spray tube and said first and said second valve for engaging and closing said second valve and thereafter engaging and opening said first valve in response to the projecting travel of said spray tube and for closing said first valve and thereafter opening said second valve

in response to the retracting travel of said spray tube, a chamber on said frame disposed in communication with said supply means and said second conduit means for accumulating air under pressure upon closing of said second valve and for discharging the accumulated air and purging said spray tube upon the opening of said second valve and for supplying a continuous trickle of air to said spray tube while in said retracted position.

3. A furnace sprayer comprising a frame, a spray tube movably and guidably mounted on said frame and formed with a nozzle in the forward end portion thereof, a double acting air cylinder connected to said spray tube for effecting longitudinal reciprocation thereof to and from a retracted inoperative position and a projected operative position, first conduit means including a first valve for supplying a pressurized liquid additive to said spray tube, second conduit means including a second valve for supplying pressurized air to said spray tube, supply means including a remotely actuatable control valve for supplying pressurized air to said cylinder and said second conduit means, actuator means on said spray tube, a first cam on said first valve and a second cam on said second valve and longitudinally spaced from said first cam, said actuator means operable to contact and actuate said first and said second cam for sequentially closing said second valve and thereafter opening said first valve in response to the projecting travel of said spray tube and for closing said first valve and thereafter opening said second valve in response to the retracting travel of said spray tube, a chamber on said frame disposed in communication with said supply means and said second conduit means for accumulating air under pressure upon closing of said second valve and for discharging the accumulated air and purging said spray tube upon the opening of said second valve.
